Patented Feb. 27, 1923.

UNITED STATES PATENT OFFICE.

HENRY E. PELLETIER, OF NEWARK, NEW JERSEY, ASSIGNOR TO HAROLD DEPEW, OF ELIZABETH, NEW JERSEY.

AIR-COMPRESSOR VALVE.

Application filed August 13, 1921. Serial No. 491,988.

To all whom it may concern:

Be it known that I, HENRY E. PELLETIER, a citizen of the United States, residing at Newark, in the county of Essex and State 5 of New Jersey, have invented new and useful Improvements in Air-Compressor Valves, of which the following is a specification.

The principal object of this invention is to 10 provide a practical and efficient spring operated conical seated air valve and means combined therewith expediting its rapid closure when in operation.

Another object is the means provided 15 within an air valve for lubricating the moving surfaces and preventing the valve spring from rusting.

A third object relates to the peculiar 20 formation of the plunger for rapid venting of the valve and holding it against its seat when closed.

These and other objects are attained by 25 the novel construction and arrangement of parts hereinafter described and shown in the accompanying drawing forming a material part of this disclosure and in which:—

Figure 1 is a partial sectional view showing 30 the outlet valve assembled and in closed position.

Figure 2 is a transverse sectional view 35 taken on the line 2—2 of Figure 1.

Referring to the drawings in detail, the 40 numeral 10 designates a fragment of an air compressor cylinder, having a head 11 and a cylindrical compression chamber in which a reciprocating piston of conventional type normally operates. Formed partially through the cylinder head 11, at a spaced distance from the center of the cylinder, longitudinally of the center line of the compressor, is a bored cylindrical opening 12, its inner end terminating in an angularly restricted opening 13 communicating with the compression chamber 14 and forming a 45 conical seat for the valve 15.

The outer end of the opening 12 is provided with screw threads adapted to engage the valve cap 16, its outer portion being squared to receive a wrench for tightening 50 and in the opposite end, concentric with the threaded portion of the cap, is a drilled hole 17. Reciprocatively slidable within the opening 12, by the action of the compressor piston, is a cylindrical bodied valve plunger,

generally designated by the numeral 15, 55 comprising a conically bevelled flat pointed plug end 18, suited to the seat 13, adjoining which is a narrow cylindrical surface 19 leading to the lower edge of an annular groove 20, its arcuate cross section having 60 a relatively large area, preferably approximating one fourth that of the valve body.

A drilled hole 21 is concentric with and extends into the body 15 from its upper end and is counterbored approximately one half 65 its length, forming a reservoir 22 for holding lubricating oil.

The valve plug end 18 is held in normal engagement against the seat 13 by the pressure of a helically coiled compression spring 70 24, operatively confined within the holes 17 and 21 respectively of the cap 16 and the valve 15, the oil maintaining the spring well lubricated and tending to prevent crystallization. 75

An outlet or exhaust port 25 passes through the wall of the compressor 10 at a right angle to the valve chamber 12 and its axis is in approximate alignment with the outer edge of the groove 20 when the valve 80 is in a closed position, and fitting the screw-threaded port 25 is a pipe 26 leading to a reservoir for air passed from the compressor through the outlet valve as described.

In operation such valves move at a rapid 85 rate, at a high frequency, and in order to attain their greatest efficiency, must close at the instant the compressing piston has completed its full stroke; this is partially accomplished by the compression spring, the 90 effect of which is materially augmented by the air pressure blast from the reservoir, back through the pipe 26, impinging on the lower portion of the annular groove 20 and acting to effect instantaneous closure of the 95 valve when pressure is removed from its end exposed to the cylinder, this being the purpose of the groove and its relative position with respect to the outlet.

From the foregoing it will be seen that 100 a simple device for this purpose has been disclosed in the preferred form of its embodiment, but it is not desired to restrict the details to the exact construction shown, it being obvious that changes in shape and 105 proportion, not involving the exercise of invention may be made without conflicting with the scope of the appended claim.

Having thus described my invention, what I claim as new and desire to secure by Letters Patent, is:—

A cylindrical valve plug, operable within a chamber, cone shaped co-operative elements integral with said valve and said chamber, spring means for closing said valve, a recess formed in the valve plug adapted to hold a lubricant, preventing rusting of the spring and automatically lubricating the valve, an annular groove of arcuate cross section formed in said valve plug

adjacent its conical portion, and a port in said chamber, the center of said port being in a plane approximately level with the upper edge of said groove when the valve plug is against its seat. ¹⁵

This specification signed and witnessed this 12th day of August, 1921.

HENRY E. PELLETIER.
